OUTLET FIXTURE

Albert W. Franklin, New York, and Charles Lancer, Woodhaven, N. Y.

Application July 3, 1931, Serial No. 549,510

2 Claims. (Cl. 247-3)

This invention relates in general to improvements in electrical outlet fixtures.

The general object of this invention is the provision of a novel form of electrical outlet fixture for use in rooms and constructed so that it can be installed so as to permit outlet connections at substantially any point in a room.

These and many other objects as will appear from the following disclosure are secured by 10 means of this invention.

This invention resides substantially in the combination, construction, arrangement and relative location of parts all as will be described in greater detail below.

16 Referring to the drawings—

Figure 1 is a front elevation view of the invention as applied to a baseboard;

Fig. 2 is a cross-sectional view taken on the line 2—2 of Fig. 1;

20 Fig. 3 is an enlarged cross-sectional view through the conductor conduit;

Fig. 4 is a bottom plan view of the conduit;

Fig. 5 is a top plan view with the cover removed;

25 Fig. 6 is a floor plan of a room showing the electrical circuit made available by invention;

Fig. 7 is an enlarged view of a modified form of the invention.

With the present form of electrical outlet boxes as used in houses and other buildings provision 20 is only made for one or two plug-in connections at one fixture. In view of the expense of these fixtures and the extra wiring which is required when more than one is used it is quite frequent that only one or two of such outlet fixtures are 35 provided in a room. The result is that appliances employing electric current must be more or less grouped about these outlets, or, if located some distance from them require longer cables to permit of connection which is unsightly and constitutes a fire hazard. The general object of this 40 invention is the provision of a novel form of outlet fixture preferably associated with the baseboard of a room which will permit of the connection of electrical appliances thereto at substantially any point in the room without requiring long connecting cables.

The nature of the invention will best be understood by direct reference to the drawings.

At 1 is shown the studding usually employed in 50 building construction upon which the walls are supported. Secured to these studdings in the usual manner are the lath 2, to which the plaster wall 3 is secured. At this point it should be noted that the invention is not limited to the particular 55 form of wall construction and that given in the

drawings is only by way of illustration. At 4 are indicated the ground boards which are usually secured to the studding and to which, in turn, is secured the baseboard. As shown in Fig. 2 the baseboard for two adjacent rooms is provided 60 comprising the lower sections 5 and the upper section 7 in the form of a molding. Mounted between these pieces which are secured to the ground boards are the outlet fixtures of this invention indicated generally at 6.

The construction of the fixture is shown in detail in Figs. 3 to 5 inclusive. It may be of any suitable insulating material, of which there are many useable forms. By way of example, a laminated phenolic condensation product which 70 is well known may be employed. The fixture comprises a channel container comprising two chamber forming legs 7 united at their adjacent sides by means of the transverse wall 8. The structure provides two rectangular channels 9 75 within which long spring contact conducting strips 12 are mounted. At 10 is a cover for the channel provided at spaced intervals with suitably shaped openings 11 through which the prongs of the plug connector are passed into contact with the resilient strips 12. With this arrangement this fixture may be extended entirely 80 around the room and provided at suitably spaced intervals with the prong receiving openings 11. The circuit arrangement for a two-door room is shown in Fig. 6. Electric circuit 85 connection can be made to the strips as indicated at the points 14 in Fig. 6. Although only single circuit lines are shown in Fig. 6 there are, of course, two of these representing each strip 90 extending around the room. With this structure it is apparent that electrical appliances may be connected into circuit at most any point in the room without requiring a long connecting cord.

A slightly modified arrangement is shown in Fig. 7 where the baseboard 20 is made in a single piece and longitudinally grooved to receive an insulating channel 21 of a different form which is provided with a removable insulating cover 22. As before, the channel is provided with two separated chambers in which the flexible contact strips 12 are mounted. In this case instead of providing outlet openings which will receive the prongs of only one plug connector, the outlet openings are shown in the form of slots 23 of such a length that more than one plug connector can be inserted at one point if desired.

It is, of course, apparent from the above disclosure that the invention is in no sense limited

to the materials employed nor to the exact structure as indicated by Figs. 2 and 7. The invention is also applicable to baseboards made of metal, for example, which can be preformed to provide the groove or space in which the fixture is mounted.

In the above disclosure it will be apparent that this invention resides in certain principles of construction and operation which may be carried out in other physical forms and we do not, therefore, desire to be strictly limited to the disclosure as given for purposes of illustration.

What we seek to secure by United States Letters Patent is:

15 1. An electrical outlet fixture as described comprising a thin strip of insulating material bent to form a U-shaped channel with portions of the legs of the channel bent back upon themselves to form reversed U-shaped channels, a metal con-

ducting strip in each of the reversed channels and a cover plate for the reversed channels having a plurality of spaced openings therein.

2. An electrical outlet fixture as described comprising a long thin strip of deformable insulating material bent along its longitudinal axis into a U-shaped channel, the free legs of the channel having portions thereof bent back in reverse direction to provide a pair of reversed channels opening on the opposite side of the strip with respect to the first mentioned channel, a transversely curved metal conducting strip mounted in each of the reversed channels and a cover plate enclosing the open ends of the reversed channels and having a plurality of pairs of disconnected openings opposite the reversed channels.

ALBERT W. FRANKLIN.
CHARLES LANCER.
